UNITED STATES PATENT OFFICE.

STANLEY W. LAWTON, OF NEW YORK, N. Y.

PHOTO-PLAY ORCHESTRAL DIRECTOR.

1,194,517.

Specification of Letters Patent. Patented Aug. 15, 1916.

Application filed September 28, 1915. Serial No. 53,118.

To all whom it may concern:

Be it known that I, STANLEY W. LAWTON, a citizen of the United States of America, residing at New York, N. Y., have invented 5 a new and useful Improvement in Photo-Play Orchestral Directors, of which the following is a specification.

It is customary to provide orchestral accompaniment for photo-plays or feature films as they are sometimes called. The ideal accompaniment would of course consist of music composed or adapted especially for the different scenes. Usually it 10 consists of selections or excerpts arranged to correspond in a general way with the character of the play and modified in accordance with the skill of the conductor or leader. In any event it is necessary for the 15 leader to be very familiar with the picture and to watch it constantly owing to the very rapid changes in scenes and irregularity in the rate of movement of the film.

My main object is to provide a system and apparatus for automatically directing the 20 leader and the orchestra in accordance with a previously laid out arrangement corresponding with the changes in scenes of the play so as to produce the desired effects.

According to my plan in its preferred 25 form a "director chart" is prepared of a length corresponding to the length of the play. This chart is marked for selections expression, tempo, changes and special directions at appropriate intervals and may 30 also be marked with a program of suitable music prepared according to the general character of the play. Pegs are then set up in a drum in sequence corresponding to the markings on the chart. The drum is 35 driven synchronously with the film of the projecting machine for operating switches controlling electric circuits through lamps giving signals indicating the desired selections, tempo, expression, directions, etc.

The direction chart is preferably in the 40 form of a strip adapted to be attached to the switch operating drum. The apparatus may be so adjusted that the indications will operate slightly in advance of the corresponding picture changes in order to give 45 the conductor time to make the necessary musical changes.

A special signal device may be provided for any individual, for instance, the drummer or an organist, located at the most convenient place for the individual and oper-

ated by one of the switches from the machine so as to enable the individual player to produce the proper effect at the proper time without watching the screen.

The accompanying three sheets of drawings illustrate certain features of the preferred form of my invention and certain modifications thereof.

Figure 1, is a diagrammatic view illustrating parts of the apparatus and the system. Fig. 2, is a vertical projection showing the directing and controlling drum and the signal apparatus, parts being broken away to show the interior construction. Fig. 3, is a side view of the same showing parts in section. Fig. 4, is a sectional view on the plane of the line 4-4 of Fig. 2 on a larger scale of part of the apparatus for indicating the sequence of pieces to be 70 played. Fig. 5, is a plan view and partial section on the plane of the line 5-5 of Fig. 2. Fig. 5^a is a detail elevation of the switch designating panels. Fig. 6, is a detail view of a fragment of the director strip 80 and controlling drum. Fig. 7, is a plane view and section on the plane of the line 7-7 of Fig. 8 of a modified form of driving and speed regulating mechanism. Fig. 8, is a side view of the same, parts being broken 85 away.

The mechanism employed may be embodied in different forms, for instance, for indicating the order or sequence of the different pieces of music to be played, I may 90 use one or more disks such as 10-10 bearing consecutive numbers, letters or other indicating devices, such as the numbers 2, 3, etc., (Fig. 2) arranged to rotate within a casing 95 11 which is provided with windows or openings such as 12-12 through which the opaque numbers on transparent backgrounds may be seen when the light 14 is lighted. The disks 10 may be driven intermittently by an electromagnet 15 having an armature 100 16 pivotally supported and connected to a pawl member 17 adapted to operate the ratchet 18 connected to or carried by one of the disks 10. The circuit through the light 14 and magnet 15 is controlled by a 105 switch having a spring finger 19 and a pivoted finger 20 adapted to be raised into contact therewith, and a suitable source of current such as 21 is provided. Other lights such as 25 may be provided in a casing 26 110 behind opaque letters, words, or abbreviations for indicating changes in tempo, ex-

- pression, such as F. P. VIV. The following is given as a typical set of designations to be employed which, of course, may be suitably abbreviated; Warning, Play, A $\ddot{\text{a}}$ tempo, Read cue, Vivace, Allegro, Moderato, Andante, Adagio, Tremolo, Segue, Pianissimo, Forte, Drum, Organ. These designations are preferably arranged behind a dark glass, for instance, ruby or red glass 10 27, so that they are not noticeable except when a light is shining within the casing behind that particular designation. One or more warning or special lights may be provided as at 29 and 30. Each light is 15 suitably electrically connected to a switch similar to the one above described. All of the switches are arranged in a casing 31 with suitable designating panels to denote the particular lights or signals to which they 20 are connected. (See Fig. 5^a).

Beneath the switches is arranged a drum 35 rotatable on a horizontal axis and provided with circumferential rows of recesses, such as 36, directly beneath the different 25 switches. These recesses are adapted to receive pegs or pins, such as 37, for operating the lower switch fingers 20, and thus closing the different indicating or signal circuits as the pegs pass beneath the fingers 20 and lift 30 them into contact with the fingers 19. The drum 35 is provided with ratchet teeth 38 adapted to be intermittently operated by a pawl 39 carried by the armature 40 of the magnet 41. A spring 42 pulls the armature and pawl away from the magnet. An adjustable back stop 43 may be provided for the armature and pawl. A friction drum 44 and an adjustable brake 45 may be provided to steady the movement of the drum 35 and 40 prevent it from spinning under the impulse of the pawl 39, or from turning backward when the pawl is retracted by the spring 42.

The drum 35 is driven synchronously with the moving picture machine or machines, by means, for instance, such as shown in Fig. 1. Here the shafts 50—50 are mechanically driven by or connected with or form part of the moving picture machine mechanism (not otherwise shown). A worm 50 51 on the shaft 50 meshes with a worm wheel 52 carrying a pin 53. A switch in the circuit with the magnet 41 has a stationary contact 54 and a movable contact 55 adapted to be pressed against it by the pin 53, so as to 55 complete the circuit through the magnet and thus draw over the pawl 39 and intermittently move the drum 35, a suitable source of electric current 56 being provided. A hand switch 57 may be provided for opening the 60 circuit. If two moving picture machines are employed, as are customary, each will control a switch within the circuit of the magnet 41. In this way the controlling drum 35 will be driven step by step at a 65 rate exactly proportional to the speed of the

film of the play being projected by the projecting machine.

The record strip 60 is ruled off longitudinally to correspond with the different signals which it is desired to convey. The 70 strip is also ruled transversely, for instance, to correspond with every minute of time and preferably is numbered on the transverse rows, as shown in Fig. 6. This strip is adapted to be secured to the drum 35, for instance, by means of a clip 61 having a hooked end 62 adapted to be inserted in a hole 63 in the drum. The part 64 is adapted to snap over the edge of the drum to assist in holding the clip in place. A guide or 75 ruler 65 may be provided in the casing 31 vertically adjustable above the strip 60 on the drum. Pegs are set up in the holes 36 in the drum to correspond with the markings on the chart or record strip 60. Preferably, the drum and switches are mounted directly beneath the signal lights at the leader's stand in the pit, but it will be obvious that they might be located at any convenient point, it simply being necessary 80 to connect the switches electrically with the lamps.

In the modification shown in Figs. 7 and 8 the drum 35 may be driven for instance, by means of a motor 70 with a suitable regulating mechanism. A friction strap 71 is provided with an adjustable weight 72 for regulating the load on the motor. The pawl 73 is driven through a mechanism shown in Figs. 7 and 8. The worm 74 on the motor 100 shaft meshes with a worm wheel 75 on the shaft with the pinion 76. This pinion meshes with gear 77 on the shaft with the toothed cylinder 78. The pawl 73 is pivoted at 79 and connected by a slotted link 80 to a disk 81 on the shaft 82. On this shaft is arranged a series of gears such as 83 of different diameters. An intermediate gear 84 is adapted to mesh with the toothed cylinder 78 and with any one of the gears 83. This intermediate 110 gear 84 is carried by a hanger 85 which is pivoted to the arm 86 so as to permit it to swing. The arm 86 is hinged on the rod 87 so that it may be slid back and forth to permit the gear 84 to be intermeshed with any 115 one of the gears on the shaft 82. The position shown in Fig. 7 is for the normal speed of operation. If the film or picture is moving more rapidly than the normal rate, the arm 86 and intermediate gear 84 are moved 120 in the direction of the word "Fast" in Fig. 7 and vice versa in the direction of the word "Slow" if the picture is moving slower than normal. To hold the arm 86 and intermediate gear in adjusted position I have 125 provided a leg 87 depending from the arm 86 which is adapted to fit into any one of the slots 88 in the plate 89, the slots corresponding with the different intermediate gears. In this way it is possible to make the con- 130

trolling or directing drum above at a greater or less speed to correspond with the rate of movement and changes of the picture.

According to my system when the photo-play is first run off the picture and directing machines are started at the same time. The orchestral leader watches the picture, writes or otherwise indicates on the paper record or director strip the pieces which he 10 wishes to be played and the exact order, time and method of playing so that when he is through rehearsing, a record is produced which can be duplicated and used by any one on a similar directing machine so as to re- 15 produce in the form of signals for the information of the leader and his men all the modifications and changes in music and tempo, in fact everything which is deemed necessary to give the proper effect to the 20 picture. With such a machine and record any leader whether familiar with the picture or not can reproduce the proper effect as determined by the expert conductor who originally rehearsed the play.

25 By using the system of lights as herein shown, signals may be given in the regular musical terms so that they cannot be misunderstood by any musician.

Owing to the fact that many pictures 30 contain very brief scenes varying radically in character, it is practically impossible to arrange ordinary music or even to mark it especially so as to correspond with the changes in scenes. By my system however, with a 35 given piece even though it is not especially arranged for a certain series of scenes, it is possible to produce exactly the right effects as the picture proceeds, for instance, right in the midst of an overture or other number, 40 if a certain part of the picture requires the orchestra to be playing loud and fast and the scene changes suddenly, perhaps for a half minute only, say to a sad scene requiring slow and soft music, the machine at the proper 45 instant gives the leader and his men a warning signal followed by a signal indicating the proper change in tempo at the proper time. Similarly the proper changes in tempo, etc., are indicated from time to time as required 50 and it is thus possible for the orchestra to play an entire number and to play it in the exact tempo and expression to correspond with the changes in the picture. It is thus possible to have the effect of music written 55 by the best composers and produce effects quite as satisfactory as though the music had been actually written for that particular play. The orchestra is thus guided in playing moving pictures as if they were taking 60 their cues from live performers on the stage.

In case a special production has the music written especially for it, each scene or character in the picture may have a part of music or motif written especially for it.

65 Each of these special parts or motifs will

be numbered or lettered and the mechanism arranged to display these numbers or letters consecutively at the proper times so that the orchestral leader will know when to start the corresponding music, for instance, 70 if the picture play begins with a ball-room scene the music for this would be say—#1 and the machine would be so arranged as to display #1 at the start. The orchestra accordingly plays the opening dance music 75 until #2 appears whatever length of time required. If the next scene should be a fight or struggle the #2 piece of music would be written accordingly. The machine would then be so arranged as to display the 80 signal for #2 at the proper moment thus producing the desired effect. #2 piece will then be played until the third signal appears no matter what length of time required. As soon as the #3 appears with 85 the scene, for instance a death scene requiring soft and slow music the orchestra will then play the third piece properly arranged until receipt of the signal for the next piece and so on throughout the picture. In this 90 connection it should be noted however that a given signal having been given it is not necessary for it to continue visible as the orchestra will continue to play according to the signal received until receipt of a change 95 signal.

Where the music is specially written for a moving picture it may not be necessary to employ the expression and tempo signals which it is described as inclosed in the casing 26. Where the music is made up of excerpts or pieces not especially written for the picture the expression signals are necessary and the number signals in the casing 11 (Fig. 2) may be employed if 105 desired or omitted if not necessary.

What I claim is:—

1. A photo-play orchestral director comprising the combination of a moving picture projecting machine with means driven synchronously therewith, switches operated by said means, and directing indicator means controlled by said switches in sequence with the progress of the picture.

2. A photo-play orchestral director, comprising the combination with a picture projecting machine, of musical-direction indicating means, operating means therefor, and means for driving said operating means in synchronism with the picture machine.

3. A photo-play orchestral director, comprising the combination with a picture projecting machine, of musical-direction indicating means, a controlling member therefor, a magnet for moving said member and means for energizing said magnet controlled by the picture machine.

4. A photo-play orchestral director, comprising the combination with a picture projecting machine, of musical-direction indi-

cating means an operating drum, a pawl for moving said drum intermittently, and means for moving said pawl synchronously with the picture changes.

5. In a photo-play orchestral director, the combination of a plurality of indicators, means for automatically operating said indicators to denote changes of musical-directions corresponding with the action of the 10 play and a director chart with markings corresponding with the respective indicator operating means movable with said operating means.

6. In a photo-play orchestral director, the 15 combination of indicating means, a drum, a director slip secured to said drum and having markings to denote sequential changes of musical-directions, and devices carried by said drum and adapted to be set to operate the indicating means in accordance with the markings on said director slip.

7. In a photo-play orchestral director, the combination of a stationary member having 20 a set of markings denoting musical directions, a series of indicators, switches therefor mounted respectively adjacent said markings and a member having devices movable past said switches for operating the same.

30. 8. In a photo-play orchestral director, the combination of indicating means, a drum having devices for operating said indicating means, a director strip with markings corresponding with said operating devices and a 35 clamp for said strip having a hook for engaging said drum at one edge of said strip and a shoulder for engaging said drum at the opposite edge of said strip.

9. In a photo-play orchestral director, the 40 combination of indicating means, a director strip having markings to denote sequential changes of musical-directions, a movable drum and devices for operating the indicating means carried by said drum and adapted 45 to be set on the drum to correspond with the markings on the director strip.

10. In a photo-play orchestral director, the combination of a picture projecting machine, a movable controlling member operated in synchronism with scenes projected by 50 said machine, a movable indicator, operating means for said movable indicator and control devices for said operating means carried by the movable control member and adapted to 55 be set in different positions thereon.

11. In a photo-play orchestral director, a movable control member, having supporting means on a portion of its surface for a plurality of control elements and a supporting

surface contiguous to and alongside said 60 supporting means, a director strip adapted to be laid on said supporting surface and having markings to denote sequential changes of musical-directions, control elements engageable with the supporting means 65 in position to correspond with the markings on the director strip, an indicator and control devices for said indicator operated by said control elements.

12. In a photo-play orchestral director, a 70 drum adapted to be rotated in synchronism with a picture projecting machine, and provided with perforations in one portion of the rim thereof and with a supporting surface alongside said perforated portion, an 75 indicator strip adapted to be laid on said supporting surface and having markings denoting changes in musical-directions, pegs insertible into the perforation in position corresponding to the markings on the director strip, control devices operated by said pegs, and indicating means operated by said control devices.

13. In a photo-play orchestral director, indicating lamps, contact devices for the 85 several lamps, a movable drum, a director strip adapted to be applied to said drum and having markings thereon for musical-directions and pegs for operating the contact devices adapted to be positioned on the drum 90 to accord with the markings on the director strip.

14. In a photo-play orchestral director, indicating means including a plurality of indicator lamps, and a rotatable indicator 95 disk, control devices for said lamps and indicator disk, a movable drum and control elements for operating said control devices mounted for adjustment to different positions on said drum.

15. A photo-play orchestral director comprising the combination of a moving picture machine, indicating means, a contact-making device controlled by the moving picture machine and electrical connection between 105 said contact-making device and said indicating means whereby consecutive changes of scene are signaled for the orchestra.

16. A photo-play orchestral director comprising the combination of a plurality of 110 moving picture machines, indicating means for signaling consecutive changes of directions for an orchestra and means for coupling any one of said picture machines at will to operate the indicating means in synchronism therewith.

STANLEY W. LAWTON.
